(57) **CLAIM**

The ornamental design for a tissue caddy as shown and described.

DESCRIPTION

FIG. 1 is a perspective view of the tissue caddy;

FIG. 2 is a front elevational view thereof;

FIG. 3 is back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8. is a second perspective view of the tissue caddy, showing a top portion separated from a base portion thereof. The broken lines in the figures show portions of a tissue caddy and form no part of the claimed design.
